UNITED STATES PATENT OFFICE.

HANS HANSON, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,271,311.

Specification of Letters Patent.

Patented July 2, 1918.

Application filed February 12, 1912. Serial No. 677,053.

To all whom it may concern:

Be it known that I, HANS HANSON, a citizen of the United States, residing in Hartford, in the county of Hartford and

5 State of Connecticut, have invented certain new and useful Improvements in Combined Type-Writing and Computing Machines, of which the following is a specification.

This invention relates to computing machines in which numeral keys are operated to set certain computation pins, the latter being subsequently employed to determine the extent of movement of the dial wheels or devices.

10 The improvement is especially adapted to combined typewriting and computing machines, and it is illustrated in connection with the Underwood-Hanson machine of this type.

15 In said machine each dial wheel is provided with a rack bar whereby it is operated; and upon each rack bar are nine pins. The keys are connected to devices for setting any of the nine pins on any of the rack bars.

20 As illustrated in patent to Hanson No. 905,421, dated December 1, 1908, the pins have been mechanically held down whenever depressed by the keys; and a universal 25 plate has been provided for subsequently forcing up to normal position all the depressed pins. A special key has also been provided for operating this pin-restoring plate, so that when an error has been made, 30 all the pins could be restored and the numeral keys could then be re-actuated correctly.

35 One of the principal features of the present invention is to provide means whereby, whenever any pin on a rack bar is depressed, it will automatically release any previously 40 depressed pin on said bar so that in making a correction it is not necessary to use an error key. Moreover it is not necessary to 45 re-write the whole number, but only to depress a single numeral key in place of the erroneously actuated key.

50 In carrying out this feature of the invention each computation pin, when depressed, is latched down. This is done by a universal latch, that is one that is adapted to lock down any of the pins on any bar. The construction is such that the depression of any pin first releases said latch, and hence re-

leases any previously depressed pin; while 55 at conclusion of the depression of the pin, the latch snaps into position to lock the same down.

In machines of this kind, the rack bars are operated by a general operator after the numeral keys have been depressed for writing and setting up any given number; and at the conclusion of the movement of said general operator, provision is made in the present machine for releasing the latches of all 65 the bars, so that all of the depressed pins may snap back to normal positions.

Other features and advantages will hereinafter appear.

In the accompanying drawings, 70 Figure 1 is a sectional side elevation from front to rear of an Underwood-Hanson combined typewriting and computing machine.

Fig. 2 is a plan of certain jacks for determining the order of operation of the computation-pin bars. 75

Fig. 3 is a part sectional side elevation of a computation pin-bar, showing one of the pins as latched down and the others in normal positions. 80

Fig. 4 is a part sectional perspective view of a portion of the pin bar, showing the first pin thereon as latched down.

Fig. 5 is a perspective view to illustrate 85 the devices connected to the general operator for automatically releasing the depressed pins at the conclusion of the cycle of movements of the general operator.

Fig. 6 illustrates the preferred form of a 90 computation pin.

Fig. 7 is a sectional side elevation illustrating the pin-releasing movement of the general operator.

Alphabet keys 1 and numeral keys 2, provided upon the forward ends of levers 3, are operated to rock bell cranks 4 to swing type bars 5 up against a platen 6. The platen is mounted upon a carriage 7, which is propelled by a spring barrel 8 and controlled in the usual manner by an escape- 95 ment wheel 9 and dogs 10, the latter operated by a universal bar 11, which is driven by heels 12 on the type bars. Dial wheels 13 are operated by pinions 14, which mesh with 100 racks 15 formed upon denominational or computation bars 16, one bar for each dial wheel; each bar carrying a set of computa- 105

tion pins 17, which are depressible by linkages 18, the latter including rock shafts 19 which have the usual arms 20 engageable by stems 21 pendent from the numeral keys 2. 5 Depression of any numeral key 2 to operate its type bar causes the depression of the corresponding linkage 18, whereby one of the pins 17 is depressed in the path of a bar 22 on a general operator 23, which is operated by a crank 24 after all of the desired pins 17 have been set. The crank is fixed upon a rock shaft 25; and the shaft carries a segmental gear 26, which meshes with an idle pinion 27, the latter meshing with the rack 10 23 and forming part of the general operator for the computing wheels.

In order to depress or set one of the pins 17, however, its bar 16 must be lifted above the other bars; and this is done by a denomination-selecting mechanism, which is controlled by the typewriter carriage 7 in conjunction with the numeral keys 2.

Upon the carriage is a dog 28 which, during the letter feeding movements of the carriage, raises denomination selecting jacks 29 one after another, and these jacks depress links 30 whose lower ends are pivoted to levers 31 which operate linkages 32 to elevate the pin-carrying bars 16; the linkages 32 forming a transposition device whereby the order of operation of the bars 16 is reversed, the extreme right hand jack 29, which is the first to be operated, causing the lifting of the extreme left hand pin carrying bar 16, as usual. The bars 16, with their pins 17, form an item register or indexing device on which digits are set up temporarily. Each pin may be also regarded as part of an indexing device for its 40 bar 16.

Each of the bars 16 is provided with a series of vertical perforations 33 to form bearings for the body portions 34 of the computation pins 17; and said perforations 45 33 may be of square form as illustrated, although the invention is not limited to such form.

The pins are held up in normal positions by compression springs 35 which bear up 50 under heads 36 secured upon the tops of the pins and are engageable by the linkages 18. At their lower ends the springs 35 bear upon a plate 37 which is supported upon the bar in raised position, being fixed to lugs or 55 elevations 38, 39, 40 formed or provided on the bar. The upward or return movement of each pin is limited by a shoulder 41 formed thereon.

Whenever any computation pin 17 is 60 pressed, its shoulder 41 catches under a latch 42, so that the pin is held down. This latch 42 is adapted to latch down any of the pins, and hence is in the nature of a universal latch. It may be formed of a strip of 65 sheet metal mounted to slide endwise along

the bar 16 and having a series of perforations 43, one for each of the computation pins 17. A draw spring 44 is connected at one end to the universal latch and at the other end to the part 40 of the bar 16, and tends constantly to move said latch to pin-locking position. The septums 45 between the perforations 43 are the members which lock the pins down; and they are preferably beveled as at 46, and each shoulder 41 has a beveled under side, as at 47, so as to cam the universal latch forwardly during the depression of any pin. At the completion of the down stroke of the pin, the universal latch 42 snaps rearwardly and catches over the shoulder 41, as seen at Figs. 3 and 4. The computation pin is thereby held down until it can be engaged by the cross bar 22 of the general operator, when it serves as a lug whereby said cross bar advances said 80 bar 16 and rotates the dial wheel 13.

The perforations 43 in the universal latch 42 are elongated to permit the necessary shifting of the latch. The latter may be confined at one end in a slot 48 in the lug 38, and at the other end may work in a bearing 49 in the bottom of lug 39; or the latter may be secured to the bar 16 by means of a pin 50, passing through a slot 51 in the end of said latch bar or member 42. If an error has been made, the operator need not press the error key, but after resetting the typewriter carriage may immediately strike the right numeral key; and the depression thereof will force down another one of the pins 17, and the cam 47 on the latter will force forwardly the latch bar 42, causing the latter to release the previously depressed pin, so that the latter is automatically returned to normal position by its spring 35; and the spring 44 will snap the latch 42 under the newly depressed pin, locking the same down in working position. The pins are shown as fitting loosely in the bearings 33 in the bar, but it will be understood that the fit will be close enough to insure proper operation of the parts. Each pin may, if desired, be formed with a slight projection 52, Fig. 6, to give the latch 42 a little additional release motion, to insure that the previously depressed pin shall be released; the edge of the pin sloping both upwardly and downwardly from the top of the projection 52, to form cams, for this purpose.

Upon the completion of the return stroke 120 of the general operator 23, a one way acting cam 53 thereon engages a wrist 54 provided on an arm 55 and lifts said arm, together with a plate or bar 56 which is carried partly by said arm and partly by a companion arm 57, Fig. 5; said arms fixed upon a rock shaft 58 suitably mounted in the framework. The bar 56 is elevated to the Fig. 7 position during the conclusion of the return stroke of the general operator 23, and lifts up all of 130

the set of pins 59 provided one upon each of the bars 16 in front of the computation pins 17. Each of these pins 59 has a cam portion 60 which passes up through a perforation 61 in the associated universal latch bar 42, and said cam portion 60 engages the forward edge of the slot 61 and forces the latch 42 forwardly to a position to release any pin that it may be latching down; whereby it is insured that all the pins shall be in normal positions at the conclusion of the return stroke of the general operator. During the final portion of said return stroke, the wrist 54 runs off from the cam 52, and the releasing bar 56 drops, and individual springs 62 return the release pins 59 to normal positions. During the next forward stroke of the general operator 23, the cam 53 rotates about its pivot 64 without lifting the releasing bar 56; and a spring 65 then returns cam 53 to normal position.

Variations may be resorted to within the scope of the invention and portions of the improvements may be used without others.

Having thus described my invention, I claim:

1. In a computing machine, the combination with a series of numeral keys, computing wheels and a traveling carriage, of reciprocating bars for rotating said wheels, a series of pins mounted on each of said bars, means enabling said pins to be set by said keys, means for driving said bars to turn said wheels to an extent determined by the pins set, and means under control of said carriage for enabling a key to modify the setting of the pins on any rack bar.

2. In a computing machine, the combination with a series of computing wheels, of reciprocating rack bars for rotating said wheels, a series of pins mounted on each of said bars, a series of typewriter numeral keys, means enabling any of said keys to set any of said pins, and means enabling the setting of one pin to restore another previously set pin on the same bar, said means including a latch on each bar universal to all of the pins thereon, and a shoulder on each pin arranged to move said latch to release any pin latched, said shoulder being formed with a cam surface, so as to allow the released pin to move to released position, said shoulder also having a surface to catch said latch to hold any pin in set position.

3. In a computing machine, the combination with a series of numeral keys, computing wheels and a traveling carriage, of reciprocating bars for rotating said wheels, a series of pins mounted on each of said bars, means controlled by said carriage for enabling any key to set any pin, and means also controlled by said carriage for enabling any key to release any pin previously set.

4. In a computing machine, the combina-

tion with computing wheels, of rack bars, numeral keys, pins settable on said rack bars by said numeral keys for determining how far said rack bars shall be moved to turn said computing wheels, a general operator 70 for driving said rack bars to an extent determined by the pin set, a spring for returning each pin to normal position, a latch individual to each rack bar for holding any pin in set position, means controlled by said general operator for returning all of said rack bars to normal position, and means brought into action when said rack bars reach normal position for releasing all of said latches.

5. In a computing machine, the combination with numeral keys and computing wheels, of rack bars for determining how far said computing wheels shall be turned, pins settable on said rack bars by said keys 85 for determining how each rack bar shall control its computing wheel, means on each rack bar for releasing the set pins, a general operator for causing said computing wheels to be rotated as determined by said rack 90 bars, and means on said general operator for operating each releasing means after the computing wheel has been turned.

6. In a computing machine, the combination with a framework and computing 95 wheels mounted therein, of rack bars controlling said computing wheels, pins settable on each rack bar, numeral keys arranged to selectively set said pins to determine how each rack bar shall control its computing 100 wheel, a releasing device on each rack bar, a universal bar on said frame adapted to operate said releasing devices, a general operator for causing the computing wheels to be operated in a manner determined by said 105 rack bars, and means on said general operator for operating said universal bar.

7. In a computing machine, the combination with an array of computing wheels, of an array of rack bars for determining how 110 said computing wheels shall operate, pins settable on said rack bars for determining how said bars shall control said wheels, a universal latch common to all the pins on one bar, a releasing device on each bar, a 115 general operator, and a universal bar moved by said general operator to operate all said releasing devices.

8. In a computing machine, the combination with reciprocating computation members and settable pins thereon, of a universal latch for the pins on one reciprocating member, a general operator for said reciprocating members, a universal bar for operating all said latches, and means on said general 125 operator for operating said universal bar.

9. In a computing machine, the combination with computing wheels and rack bars for determining how far said computing wheels shall rotate, of pins settable on said 130

rack bars, said pins forming a series of rows, a universal latch on each rack bar for holding any pin set thereon, a releasing device for each latch, a general operator for said 5 rack bars, and a device for simultaneously operating all said releasing devices, operable by said general operator.

10. In a computing machine, the combination with a series of reciprocating members, 10 of a general operator for said members, pins settable on each member for determining how far the general operator shall operate said member, means on the said general operator for returning said members to their 15 normal position, a universal latch on each member for holding set any pin thereon, and a universal bar common to all said latches and operated when said members are all at their normal ineffective position to release 20 said latches.

11. In a computing machine, the combination with an array of reciprocating members, of a set of pins on each member, a general operator for said members driving each 25 member to an extent determined by the pin set thereon, a bar on said general operator for returning said members to their normal position, a universal latch for the pins on each member, a universal bar cooperating 30 with all said latches to release the pins, and a cam on said general operator arranged to move said universal bar to its effective position momentarily after said general operator has returned said members to their normal 35 position.

12. In a combined typewriting and computing machine, the combination with keys operating types, of a traveling carriage controlled by said keys, a series of reciprocating 40 members driving computing-wheels, an array of settable pins on each of said members determining how far it shall drive its computing-wheel, means for setting said pins for said keys in an array selected by 45 said carriage, a universal latch on each of said members to hold any pin set by said keys and arranged to release any previously set pin on said member when any other pin is set, a general operator for causing said 50 members to drive said computing wheels, and means controlled by the completed movement of said general operator for releasing every set pin.

13. In a combined typewriting and computing machine, the combination with keys operating types, of a traveling carriage controlled by said keys, a series of reciprocating members driving computing wheels, an array of settable pins on each of said members determining how far it shall drive its computing wheel, means for setting said pins from said keys in an array selected by said carriage, a universal latch on each of said members to hold any pin set by said keys 65 and arranged to release any previously set

pin on said member when any other pin is set, a releasing pin in each of said arrays operating said universal latch, a bar common to all of said releasing pins, a general operator for causing said members to carry 70 into the wheels the numbers represented by the pins set, and means controlled by the completed movement of said general operator for causing said bar to operate said releasing pins and release all the set pins. 75

14. In a combined typewriting and computing machine the combination with keys operating types, of a traveling carriage controlled by said keys, a series of reciprocating members driving computing wheels, an array 80 of settable pins on each of said members determining how far it shall drive its computing wheel, means for setting said pins from said keys in an array selected by said carriage, a universal latch on each of said members to hold any pin set by said keys and arranged to release any previously set pin on said member when any other pin is set, a releasing pin in each of said arrays operating its universal latch, a general operator 85 for carrying into said wheels the numbers represented by the pins set, a bar common to all said releasing pins but normally spaced therefrom, a member pivoted on said general operator and arranged to pass idly by said releasing bar as said numbers are carried into said wheels, and means for causing said cam to operate said releasing bar on the return stroke of said operator. 90

15. In a computing machine, the combination with computing wheels, of reciprocating bars for turning said computing wheels, a series of digit pins on each bar for determining how far said bars shall move, a controller pin carried by each bar, and means 105 controlled by said pin for holding any of said first-mentioned digit pins in set position while any bar is moving to control its computing wheel, said controller pins causing release of the digit pins of its corresponding 110 bar after a computing action of said bar is completed.

16. In a computing machine, the combination with computing wheels of reciprocating bars for turning said computing wheels, a series of digit pins spring-held in normal inactive positions on each of said bars, a latch for holding any pin in set position against the action of its spring, means co-operating with the set pin to move said bar a distance determined by the set pin to turn the computing wheel associated with said bar, and a controller pin on each bar having means thereon to co-operate with the latch on its corresponding bar to release any set pin. 120

17. In a computing machine, the combination with computing wheels, of reciprocating bars for turning said wheels, a series of digit pins spring-held in normal inactive positions on each bar, means for setting any 130

one of said digit pins, a general operator for co-acting with the set pin to drive said bar a distance determined by said pin to thereby turn the computing wheel associated with

5 said bar, a latch for holding any pin in set position against the action of its spring, a controller pin for each reciprocating bar co-operating with the latch on said bar to release any digit pin, and means controlled by 10 said general operator for moving all of said controller pins to thereby release the latches of all of the reciprocating bars.

18. In a computing machine, the combination with computing wheels, of reciprocating bars for turning said wheels, a series of digit pins spring-held in normal inactive positions on each bar, means for setting any one of said digit pins, a general operator for co-acting with the set pin to drive said bar a 20 distance determined by said pin to thereby turn the computing wheel associated with said bar, a latch for holding any pin in set position against the action of its spring, a controller pin for each reciprocating bar co-operating with the latch on said bar to release any digit pin, means controlled by said general operator for returning all of said reciprocating bars to normal position, and means controlled by said general operator 25 when said reciprocating bars have been returned to position to move all of said controller pins to release said digit pins.

19. In a computing machine, the combination with numeral wheels, of reciprocating bars for turning said wheels, a series of digit pins on each bar for determining the amount of movement thereof, a series of digit keys, means controlled thereby for setting a digit pin on any bar corresponding to the key operated, means enabling any other key to set its digit pin on any bar and replace any previously set pin on the corresponding bar and a controller pin carried by each reciprocating bar for also releasing any set digit pin 45 on its corresponding bar.

20. In a computing machine, the combination with computing wheels, or rack bars for turning said wheels, a series of settable digit pins on each rack bar, means for setting pins 50 on different rack bars corresponding to the digits of a number to be computed, means for engaging the digit pins so set and moving the rack bars to positions determined by the set pins, a universal latch on each rack bar for holding any pin thereon in set position, means to restore all of said rack bars to alined position at the end of a computation, and means brought into action when said bars are so alined for moving all of said 55 latches to release any set pins.

21. The combination with a computing head, of actuating mechanism for running up numbers on said computing head, a series of pins settable in one direction to determine the extent of movement of said actu-

ating mechanism, and pin means settable in the opposite direction to determine the unsetting of said pins.

22. The combination with a series of computing wheels, of a series of denominational members, one for each of said computing wheels, a series of pins for each of said denominational members, said pins being settable in one direction to determine the extent of movement of said denominational members, and a pin for each of said denominational members settable in the opposite direction to determine the unsetting of said first-mentioned pins. 70 75

23. The combination with a series of computing wheels, of a series of denominational members, one for each of said computing wheels, a series of pins for each of said denominational members, said pins being settable in one direction to determine the extent of movement of said denominational members, a pin for each of said denominational members settable in the opposite direction to determine the unsetting of said first-mentioned pins, and means for actuating said last-mentioned pins after said first-mentioned pins have completed the computing operation for which they were set. 80 85 90

24. The combination with a series of computing wheels, of a series of denominational members for determining the actuation of said computing wheels, a series of pins for determining the extent of movement of said denominational members, means for setting 95 said pins, a general operator for driving said denominational members amounts determined by the pins set, a series of unsetting members, one for each of said denominational members, for enabling the unsetting of said pins, and an interponent mechanism interposed between said denominational members and said general operator, so as to be actuated by said general operator and arranged to actuate said unsetting members to enable the unsetting of the set pins. 100 105 110

25. The combination with a series of nine digit keys, and a set of indexing devices arranged in denominational rows, of a set of bars carrying said indexing devices, one bar 115 for each row thereof, each of said bars individually displaceable to bring the indexing devices thereon out of register with the indexing devices on the remaining bars, a key-releasable universal index-latching means 120 mounted on each of said bars, and a key-operated bar transverse to said denominational bars, to actuate any of said indexing devices and cause said universal latching means to effect the restoration of any erroneously set indexing devices on the same bar; means being provided to displace any of said bars selectively, for the purpose of making a correction. 125

26. The combination with a series of nine 130

- 6
- digit keys, and a set of indexing devices arranged in denominational rows, of a set of bars carrying said indexing devices, one bar for each row thereof, each of said bars individually displaceable to bring the indexing devices thereon out of register with the indexing devices on the remaining bars, a key-releasable universal index-latching means mounted on each of said bars, a key-operated bar transverse to said denominational bars, to actuate any of said indexing devices and cause said universal latching means to effect the restoration of any erroneously set indexing devices on the same bar, a letter-feeding carriage controlled by said keys, and means operatively associated with said carriage for displacing said bars successively, whereby after any key is depressed and a corresponding indexing device set, the carriage, by reason of its letter-feeding movements, selects the bar of next lower denomination for displacement; said carriage being capable of adjustment in either direction to selectively control the displacement of the denominational bars, to enable any one of said keys to effect the restoration of any erroneously set indexing device in the system.
27. In a combined typewriting and computing machine, the combination with a set of typewriter digit printing keys ranging from one to nine, of a traveling typewriter carriage, denominational members on which the typewriter carriage is adapted to act as a denomination selector, an indexing device associated with each denominational member whereby the digits printed by the typewriter are registered, and means associated with said indexing device whereby if the typewriter carriage is brought back as a denomination selector, any of said digit keys when operated to print in said denomination will release the registering of any digit registered in said denomination, so that the typewriter carriage becomes a denomination selector for correction purposes.
28. In a combined typewriting and computing machine, the combination with a traveling typewriter carriage, nine digit typewriter keys and a set of computation members, of a row of indexing devices on each of said computation members, means whereby upon the setting of any indexing device each computation member automatically unsets every other device on said member, said carriage settable to select a computation member on which the keys will be effective and to concomitantly select a printing point for said keys, to correct the printing and setting at that point.
29. In a computing machine, the combination with computing wheels, of rack bars for turning said wheels, a series of digit pins on each rack bar, means for setting a pin on any rack bar, means for detaining any pin in set position, means for engaging said pins and moving the rack bar to an extent determined by said pin, a device on each rack bar adapted to be aligned when said bars are aligned, and means co-operating with said aligned devices at the completion of a computation for releasing all of said pins.
